Primary Examiner — Mary Ann Calabrese*(74) Attorney, Agent, or Firm* — Fitch, Even, Tabin & Flannery LLP(57) **CLAIM**

I claim the ornamental design for a table, as shown and described.

DESCRIPTION

FIG. 1 is a top perspective view of a table, showing my new design;

FIG. 2 is a bottom perspective view thereof;

FIG. 3 is a front elevational view thereof, the rear elevational view and the right and left elevational views being identical;

FIG. 4 is a top plan view thereof;

FIG. 5 is a bottom plan view thereof;

FIG. 6 is a cross-sectional view thereof taken along line 6-6 in FIG. 3; and,

FIG. 7 is a cross-sectional view thereof taken along line 7-7 in FIG. 3.

1 Claim, 7 Drawing Sheets(56)
